UNITED STATES PATENT OFFICE

ARCHIBALD ALLAN, OF NORTH SHIELDS, ENGLAND, ASSIGNEE TO A. REYROLLE & COMPANY LIMITED, OF HEBBURN-ON-TYNE, ENGLAND, A COMPANY OF GREAT BRITAIN

INSULATING BUSHING FOR ELECTRICAL APPARATUS

Application filed March 4, 1926, Serial No. 92,269, and in Great Britain March 16, 1925.

This invention relates to insulating bushings for high voltage electrical apparatus and has for its object to prevent damage resulting from the unequal expansion of the different materials which are employed in the bushing and the parts it contains.

The insulating bushing according to the present invention comprises two external insulators in substantial alignment connected together by a member serving as a support for the bushing and a central conductor which is rigidly attached at one end to one of the insulators whilst its other end is free to slide relative to the other insulator (for example by means of a plug and socket or other sliding connection), the arrangement being such as to permit relative longitudinal movement between the conductor and the insulators due to the unequal expansion thereof.

The central conductor is preferably surrounded within the external insulators by a condenser-insulator which is carried at an intermediate point by the supporting member whilst its ends are left free to permit longitudinal movement relative to the conductor and the external insulators and to allow, to some extent, for incorrect alignment. The tubular metal core of this condenser-insulator may be connected to the central conductor by means of a flexible lead in order to maintain them at the same potential and thus relieve intermediary stress without impeding relative movement between them. The supporting member may conveniently take the form of a casing containing a protective or other transformer of the straight-through type.

Such a bushing may be used with apparatus which contains oil, and the open spaces in the bushing itself may be filled with oil. Thus, for instance, the central conductor may be one of those leading to the contacts of an oil-immersed switch or circuit-breaker. In such a case the central conductor is preferably made tubular or hollow and the socket or sliding connection at its upper end is slotted or otherwise provided with an opening, so that oil may pass from the chamber surrounding the socket into the tubular conductor or vice versa and the level of oil in that chamber may be kept approximately constant.

The bushing may be mounted on the oil tank of the switch or other oil-immersed apparatus, so that the lower insulator and the open end of the tubular central conductor are immersed in the oil, and thus the oil in the bushing and tubular conductor is in communication with that in the tank. A reduction in pressure in the chamber surrounding the socket at the upper end of the bushing will then draw oil up from the tank through the tubular conductor, and conversely an increase of pressure in that chamber would cause oil to flow down the conductor into the tank. To prevent undue pressure in the bushing due to heavy pressures in the tank when the circuit is broken the lower end of the tubular conductor may be provided with a ball or other valve, which is so arranged that it does not prevent a gradual flow of oil in either direction due say to temperature changes but prevents any rapid flow from the tank into the bushing.

The invention may be carried into practice in various ways but three alternative constructions according thereto are illustrated by way of example in the accompanying drawings, in which

Figure 1 is an elevation partly in central section of one construction,

Figure 2 is an enlarged view (partly in section) of the upper end of the bushing shown in Figure 1,

Figures 3 and 4 are views similar to those of Figures 1 and 2 but showing the second construction,

Figure 5 is an enlarged view of the lower end of the bushing shown in Figure 3, and

Figure 6 is a central section (partly in elevation) of a simpler construction intended more particularly for use in smaller bushings.

In the construction shown in Figures 1 and 2 the bushing consists of upper and lower insulators A A¹ of porcelain or like material, which are carried in alignment with one another respectively on cover B¹ and on the base B² of a transformer casing B having an external flange B³ which acts as a support for the bushing. Either insulator may be formed in two or more parts clamped or cemented to

gether (as shown at A² for the upper insulator A). The main conductor consists of a rod C rigidly attached at its lower end C¹ to the end of the lower insulator A¹ and passing centrally up through the upper end of the upper insulator A. Surrounding the central conductor C is a metal core D¹ on which is wound a condenser-insulator D of paper or other suitable material. A flange D² formed in segments which are clamped around the condenser-insulator D serves as a support therefor, the ends of the condenser-insulator being left free to allow for longitudinal or lateral movement relative to the central rod C and the external insulators A A¹. The transformer is located in its casing B around the condenser-insulator D and the secondary windings thereof are connected to terminals mounted in a box E carried on the outside of the transformer casing B. The upper end of the central conductor C is formed as a plug engaging in a socket G which is carried in the end of the upper insulator A and to which the incoming lead is connected. This socket is provided with a safety valve G¹ to relieve excessive pressures set up by abnormal conditions.

With this construction it will be seen that no undesirable strains are set up as a result of the different expansion of the various materials used due to changes of temperature, since the ends of the condenser-insulator D are free whilst the central conductor C can slide in the socket G at its upper end.

The space between the condenser-insulator D and the external insulators A A¹ is filled with oil, and in order to relieve the dielectric stress which might be set up between the conductor C and the tubular core D¹ of the condenser-insulator, these two members are connected together by a flexible lead C² which does not interfere with the relative longitudinal movement between them.

Around the socket G and the upper end of the central conductor C, the bushing is provided with a casing F having windows F¹ for the inspection of the oil level. The usual arcing ring F² is also provided.

Apart from small constructional modifications in details, the arrangement of the external insulators, the transformer and the condenser-insulator is the same in the construction of Figures 3-5 as in that of Figures 1 and 2, and the same reference letters are employed where applicable. The central conductor is however differently arranged in Figures 3-5 and will now be described.

In this construction the central conductor H is made tubular and projects through the lower end of the lower insulator A¹ to which it is connected. This lower insulator A¹, and therefore also the end of the conductor H, is intended to be immersed in the oil contained in the tank of a transformer or of an oil-break switch a contact H¹ of which is carried on the

lower end of the conductor H. At its upper end the conductor H slides in a socket K provided with slots K¹, so that the interior of the tubular conductor H is in open communication with the space within the bushing around the socket K. Thus oil is free to flow from the tank through the tubular conductor H into the bushing or vice versa, and the level of oil in the bushing will be maintained more or less constant. In order to prevent a rapid rush of oil from the tank into the bushing, such as might occur when the switch is opened, a ball valve H² is provided in the lower end of the conductor H. This valve is so arranged that it will not prevent gradual flow of oil in either direction. The conductor H is as in the other construction connected to the core D¹ of the condenser-insulator D by means of a flexible conductor H³.

Figure 6 illustrates a construction which may be employed in certain instances, more especially in the case of a smaller bushing. In this construction the bushing comprises upper and lower insulators L L¹ mounted respectively on the upper and lower ends of a transformer casing M having a flange M¹ which serves as a support for the bushing. The central conductor N is again fixed to the lower insulator L¹, but its upper end is clamped within a member N¹, the conductor N or an extension N² on the member N¹ being arranged to slide within a machined hole in the insulator L or within a metal bushing in a hole in the insulator. Connection with the external circuits may be made by any suitable means as for instance those indicated at N³ and N⁴. The central conductor N is surrounded by paper insulation O, which may be of the condenser type or not as desired. This insulation O may have its lower end fixed to the insulator L¹ and its upper end free, to allow of longitudinal movement relative to the central conductor and the external insulators.

It will be appreciated that the three constructions have been described by way of example only and that modifications may be made without departing from the invention.

What I claim as my invention and desire to secure by Letters Patent is:—

1. An insulating bushing for high voltage electrical apparatus, comprising two external insulators in substantial alignment, a connecting member between the insulators serving as a support for the bushing, a rigid central conductor fixed near one end to one of the insulators, a conducting member fixed to the other insulator, and an electrical connection between the free end of the central conductor and the conducting member which is such as to allow longitudinal expansion and contraction of the central conductor relative to the external insulators.

2. An insulating bushing for high voltage electrical apparatus, comprising two exter-

nal insulators in substantial alignment, a connecting member between the insulators serving as a support for the bushing, a central conductor which is rigidly attached near one end to one of the insulators whilst its other end is free to slide relatively to the other insulator, and an insulator surrounding the central conductor and so mounted within the bushing as to be free to expand or contract longitudinally relative to the external insulators and to the central conductor.

3. An insulating bushing for high voltage electrical apparatus, comprising two external insulators in substantial alignment, a connecting member between the insulators serving as a support for the bushing, a central conductor which is rigidly attached near one end to one of the insulators whilst its other end is free to slide relatively to the other insulator, a condenser-insulator surrounding the central conductor within the bushing, and means whereby the condenser-insulator is carried at an intermediate point by the supporting member whilst its ends are left free to permit longitudinal movement relative to the external insulators and to the central conductor.

4. An insulating bushing for high voltage electrical apparatus, comprising two external insulators in substantial alignment, a connecting member between the insulators serving as a support for the bushing, a central conductor which is rigidly attached near one end to one of the insulators whilst its other end is free to slide relatively to the other insulator, a condenser-insulator having a tubular metal core surrounding the central conductor within the bushing, a flexible conducting lead connecting the central conductor with the core of the condenser-insulator, and means whereby the condenser-insulator is carried at an intermediate point by the supporting member whilst its ends are left free to permit longitudinal movement relative to the external insulators and to the central conductor.

5. An insulating bushing for high voltage electrical apparatus, comprising two external insulators in substantial alignment, a casing serving as a connecting member between the insulators and as a support for the bushing and adapted to contain a transformer, a central conductor which is rigidly attached near one end to one of the insulators whilst its other end is free to slide relatively to the other insulator, and an insulator surrounding the central conductor and so mounted within the bushing as to be free to expand or contract longitudinally relative to the external insulators and to the central conductor.

6. An insulating bushing for high voltage electrical apparatus, comprising two external insulators in substantial alignment, a casing serving as a connecting member between

the insulators and as a support for the bushing and adapted to contain a transformer, a central conductor which is rigidly attached near one end to one of the insulators whilst its other end is free to slide relatively to the other insulator, a condenser-insulator surrounding the central conductor within the bushing, and means whereby the condenser-insulator is carried at an intermediate point by the transformer casing whilst its ends are left free to permit longitudinal movement relative to the external insulators and to the central conductor.

7. An insulating bushing for high voltage electrical apparatus, comprising a member serving as a support for the bushing, two external insulators mounted in substantial alignment with one another respectively on the upper and lower ends of the supporting member, a central conductor, means for attaching the central conductor rigidly to the end of the lower insulator, a conducting member fixed adjacent the end of the upper insulator, a sliding connection of the plug-and-socket type between such conducting member and the central conductor, and means for preventing the setting up of excessive internal pressures within the bushing.

8. An insulating bushing for high voltage electrical apparatus, comprising a casing having an external flange serving as a support for the bushing, such casing being adapted to contain a transformer, two external insulators mounted in substantial alignment with one another respectively on the upper and lower ends of the transformer casing, a central conductor, means for attaching the central conductor rigidly to the end of the lower insulator, a conducting member fixed adjacent the end of the upper insulator, a sliding connection of the plug-and-socket type between such conducting member and the central conductor, and means for preventing the setting up of excessive internal pressures within the bushing.

9. An insulating bushing for high voltage electrical apparatus, comprising a member serving as a support for the bushing, two external insulators mounted in substantial alignment with one another respectively on the upper and lower ends of the supporting member, a central conductor, means for attaching the central conductor rigidly to the end of the lower insulator, a conducting member fixed adjacent the end of the upper insulator, a sliding connection of the plug-and-socket type between such conducting member and the central conductor, means for preventing the setting up of excessive internal pressures within the bushing, and a condenser-insulator surrounding the central conductor within the bushing and carried by the supporting member.

10. An insulating bushing for high voltage electrical apparatus, comprising a member

serving as a support for the bushing, two external insulators mounted in substantial alignment with one another respectively on the upper and lower ends of the supporting member, a tubular central conductor rigidly attached to the end of the lower insulator, a conducting member fixed adjacent the end of the upper insulator, and a sliding connection of the plug-and-socket type between such conducting member and the central conductor, this sliding connection being slotted to allow oil to pass freely between the interior of the tubular conductor and the space within the bushing surrounding such conductor.

11. An insulating bushing for high voltage electrical apparatus, comprising a casing having an external flange serving as a support for the bushing, such casing being adapted to contain a transformer, two external insulators mounted in substantial alignment with one another respectively on the upper and lower ends of the transformer casing, a socket member fixed adjacent the end of the upper insulator, and a tubular central conductor rigidly attached to the end of the lower insulator and having its upper end formed as a hollow plug making sliding engagement with the socket member, such socket member being slotted to allow oil to pass freely between the interior of the tubular conductor and the space within the bushing surrounding such conductor.

12. An insulating bushing for high voltage electrical apparatus, comprising a member serving as a support for the bushing, two external insulators mounted in substantial alignment with one another respectively on the upper and lower ends of the supporting member, a tubular central conductor rigidly attached to the end of the lower insulator, a conducting member fixed adjacent the end of the upper insulator, a sliding connection of the plug-and-socket type between such conducting member and the central conductor, this sliding connection being slotted to allow oil to pass freely between the interior of the tubular conductor and the space within the bushing surrounding such conductor, and a valve in the lower end of the tubular conductor which acts to prevent a rapid flow of oil up the conductor but allows a gradual flow of oil in either direction past the valve.

In testimony whereof I have signed my name to this specification.

ARCHIBALD ALLAN.
